BUILDING UNIT AND CONSTRUCTION
MADE THEREFROM

Peter Ruttent, Osakis, Minn.

Application February 1, 1933, Serial No. 654,630

5 Claims. (Cl. 72—66)

This invention relates to building units and building constructions made therefrom. More specifically, the invention relates to floor constructions used in buildings.

5 It is one of the main objects of this invention to provide a novel and improved floor construction, which can be laid up as a building is erected to form a floor composed chiefly of masonry without necessitating the use of supported form boards or other temporary forms.

10 It is another object to provide such a floor construction, which can be erected by use of concrete and precast building units formed of plastic material and preferably formed chiefly from concrete.

15 It is still another object to provide novel and improved building units of precast plastic construction, which can be utilized in building the floor of the invention.

20 The objects and advantages of the invention will more fully appear from the following description, made in connection with the accompanying drawing, wherein like reference characters refer to the same or similar parts throughout the various views, and, in which,

25 Fig. 1 is a perspective view illustrating a portion of a floor of a building constructed in accordance with my invention;

30 Fig. 2 is a perspective view illustrating one of the blocks used in building the floor shown in Fig. 1;

35 Fig. 3 is a perspective view of one of the rails used in the floor shown in Fig. 1;

40 Fig. 4 is a vertical section taken through a beam of a different type than that shown in Fig. 1, said beam supporting certain parts of a floor; and

45 Fig. 5 is a perspective view illustrating yet another type of beam that may be used.

In setting up a flooring, built in accordance 50 with the present invention, I use certain precast building units of peculiar construction. These different precast building units will now be described.

55 I provide a number of long rails A which are substantially the same shape as ordinary railroad rails. Each rail A is of T-shape in vertical cross section, and it includes a pair of oppositely disposed horizontal flanges 8 and a vertical web 9 of substantially rectangular shape in cross section at its portion remote from the flanges 8 and having concave side portions intermediate the rectangular portion and the flanges 8. Each rail A is formed of precast concrete suitably reinforced by reinforcing rods 10 and bow-shaped hangers or cross reinforcing rods 11.

5 Preferably, one of the reinforcing rods 10 is located in the portion of the web 9 of rectangular shape in cross section, while two reinforcing rods 10 are buried within the flanges 8 respectively and another reinforcing rod 10 is buried in the portion of the rail where the web 9 joins the two horizontal flanges 8. The bow-shaped hangers or cross reinforcing rods 11 overlie the last mentioned reinforcing rod 10 and underlie the two reinforcing rods buried in the flanges 8. The rails 10 A may be made of any suitable length and height, depending on the requirements of the particular floor to be laid.

10 I also provide a number of blocks B of precast plastic material. These blocks are preferably 15 concrete blocks, although tile blocks, cinder blocks, gypsum blocks or the like may be used if desired. Each block B is of general rectangular shape in vertical cross section and includes top and bottom and side exterior walls 12, which form 20 the shell of the block. Longitudinal rabbets 13 are formed at the lower edges of the block and these rabbets are of sufficient depth to receive the horizontal flanges 8 of the rails A. A vertical internal web 14 runs between the central 25 portions of the top and bottom walls of the block B and diagonal internal webs 15 join the longitudinal central portion of the top wall of each block and extend downwardly to join that portion 30 of the block formed by the junctures of the bottom wall with the side walls. The three webs 14 and 15 together form a truss or brace for the block B imparting thereto great strength for carrying loads.

35 Other precast building units that are sometimes used in laying up a floor, in accordance with the invention, are concrete angle members C of L-shape in vertical cross section. These angle members C are made in rights and lefts and are generally provided with horizontal flanges of 40 shorter length than their vertical flanges.

45 I also sometimes use precast concrete building units D formed exactly the same as the rails A, but of smaller size than the rails A.

Occasionally I use a rail E, which is identically 45 of the same construction as the rails A with one of the horizontal flanges 8 eliminated.

50 Referring now to Fig. 1 of the drawing, there is shown a floor set up in a portion of a building in accordance with my invention. One of the end walls of the building is designated by the numeral 16 and this end wall is provided with a step or ledge 17. There is also shown a side wall 18 of the building. In setting up the flooring, transverse beams 19 are first laid at spaced intervals 55

longitudinally of the building between the side walls 18. Although different types of beams may be used, in Fig. 1 there is illustrated a beam constructed chiefly from my precast building units 5 C and D. In forming this beam 19, right and left hand concrete angle members C are disposed in facing relation with the horizontal flanges of the angle members spaced apart a distance corresponding to the width of the building unit D 10 whereupon the horizontal flanges of the unit D are located intermediate the horizontal flanges of the angle members C in abutment therewith. The ends of the three units C and D may be suitably supported as in notches 20 formed in the 15 side walls 8 or they may be supported in any other desired manner. After the three precast units C and D of each beam are in place, reinforcing rods 21 may be laid within the trough formed by the units, whereupon the trough may be filled 20 with concrete 22 flush with the tops of the angle members C and the concrete may be allowed to harden. The beam 19 accordingly can be made without use of form boards on the job.

After the beams 19 are in place, a number of 25 the rails A are placed in spaced parallel relation to extend longitudinally of the building and rest on the beams 19 and the shelves 17 of the end walls. Of course, when a floor of any considerable length is being laid, certain of the rails A 30 will rest at both ends on beams 19. The rails A are, of course, laid with the flanges 8 downward and the webs 9 projecting upwardly. The rails are so spaced as to receive between adjacent rails the blocks B with portions of the flanges 8 of the 35 rails received within the rabbets 13 of the blocks. The blocks B are laid in place in longitudinal parallel rows, respective adjacent blocks of the different rows being placed with their ends in abutment as shown. If the spacing between the two 40 side walls 18 of the building is somewhat greater or less than an even multiple of the center to center spacing between adjacent rails A, additional rails A or rails E, as illustrated, may be used to fill up the space between the side walls 45 18 and the block carrying rails A adjacent thereto.

After the rails and blocks have been laid, as above described, concrete 23 is poured between the side walls of the blocks B and the vertical webs 9 of the rails and if it is desired to apply 50 a wooden flooring over the masonry flooring, wooden sleepers 24 may be inserted within the concrete 23 to lie flush with the top walls of the blocks B and the upper edges of the rails 8. Of course, if any rails E are used, or if any extra rails A are used, to fill the gap between a side wall 18 and an adjacent block carrying rail A, the space between the vertical webs of these additional rails will also be filled with concrete 23 and, if desired, sleepers may be inserted in this concrete. If it is desired to lay a wooden flooring 55 over the masonry, the flooring 25 may be laid and this flooring may be nailed directly to the sleeper 24. Of course, if a concrete flooring is desired over the masonry floor above described, the sleepers 24 need not be used and the concrete floor may be applied directly over the rails A, block B and concrete 23.

It should be noted that by use of my precast building units A and B, the masonry floor, above 70 described, can be laid without use of form boards and without use of supports of any kind. It should also be noted that the bottoms of the rails A lie flush with the bottoms of the blocks B after the masonry floor has been laid and, accordingly, 75 ceiling plaster may be applied directly to the

bottoms of the rails A and blocks B without necessitating the use of lathing of any type. The diagonal webs 15 of the blocks act to transmit loads imposed upon the blocks to the flanges 8 of the rails, while the vertical webs 14 of the blocks brace and strengthen the diagonal webs 15, as well as to support the top walls of the blocks. An exceedingly strong and durable floor is thus provided. This floor is entirely fire proof except for any wooden flooring 25 that may be laid over the same and except for the sleepers 24 if the wooden flooring 25 is used.

Instead of the beam 19 illustrated in Fig. 1, a beam 26, similar to that shown in Fig. 5, may be used. The beam 26 is formed by two of the angle members C laid with their horizontal flanges in abutment, reinforcing rods 21 disposed within the trough thus formed and concrete 27 poured within the trough. If it is desired to tie the beams directly into the masonry of the floor, beams of the 20 type shown in Fig. 4 and designated by the numeral 28, may be used. When the beams 28 are used, two of the angle members C and one of the precast units D are provided for each beam and located as in the case of beam 19 to form a 25 trough. Reinforcing rods 21 are then placed within this trough, whereupon the rails A and blocks B are laid in such manner that certain of the ends of the rails and ends of certain blocks B rest on the vertical flanges of the angle members 30 C with a space provided between the rails and blocks resting on one of the angle members C and the rails and blocks resting on the other of the angle members C. Building paper or the like is then used to close the facing end openings 35 in the blocks B spaced from each other, whereupon concrete 29 is poured into the trough formed by the building units C and D and also into the space between spaced ends of the rails A and between the ends of adjacent blocks B resting on 40 the angle members C. With this construction, after the concrete 29 has set and hardened, the beam 28 forms an integral part of the masonry floor.

By reason of the fact that no form boards or 45 bracing need be used in erecting the floors of the present invention, the floors can be laid with a minimum of labor, time and expense. The floor can be almost immediately used to carry on further building operations without necessitating a 50 wait period for concrete to set.

Although my various precast building units are particularly adapted for use in connection with floor constructions, they are capable of being used in many other ways in building operations. 55

It will, of course, be understood that various changes may be made in the form, details, arrangement and proportions of the various parts and in building constructions made from the various building units without departing from 60 the scope of the present invention, which, generally stated, consists in the matter shown and described and set forth in the appended claims.

What is claimed is:—

1. A floor construction comprising a plurality of 65 spaced parallel rails of inverted T-shape in cross section, a plurality of blocks disposed between the rails in abutting lines and resting on the flanges of the rails, said blocks being rabbeted at their lower bottom edges to receive the rail 70 flanges, said blocks each including bottom, top and side walls running parallel to the rails and internal webs forming trussed bracing for the blocks, the sides of said blocks being spaced somewhat from the adjacent portions of the rails, 75

concrete substantially filling the spaces between the side walls of the blocks and the adjacent portions of the rails, sleepers embedded in the concrete and wooden flooring nailed to said sleepers.

5. 2. A fire proof building construction comprising retaining walls, transverse beams running between and supported by a pair of opposite retaining walls, each beam comprising a pair of opposed precast concrete angle members having lower horizontal flanges disposed in spaced parallel relation, a rail of inverted T-shape in cross section having horizontal flanges in abutment with the opposed horizontal flanges of the angle members to form with the angle members, a trough, a plurality of longitudinal spaced rails of inverted T-shape in cross section supported by said beams and the remaining retaining walls and terminating at certain of their ends over the 10 beams in spaced relation, blocks disposed between and supported by said rails in longitudinal abutting lines, the lines being broken above certain of said beams and concrete filling the troughs of said beams and filling the spaces between the 15 spaced ends of aligned rails and the broken lines of blocks.
3. A building construction comprising a plurality of spaced parallel rails of inverted T-shape in cross section, each rail having a central up- 20 standing web and outwardly extending bottom flanges joining the same, a plurality of blocks 25

disposed between and resting on the bottom flanges of the rails, said blocks being rabbeted at their lower bottom edges to receive the outer portions of the bottom flanges of the rails, said rabbets being of less width than the said bottom flanges to space the upstanding central webs of the rails from the side walls of adjacent blocks and concrete received within and filling said spaces and bonding rails and blocks together.

4. A building construction comprising a plurality of spaced parallel rails of inverted T-shape in cross section, each rail having a central upstanding web with channels formed in its sides and each rail also having bottom flanges joining the lower end of the central web, a plurality of 10 blocks disposed between and resting on the bottom flanges of the rails, said blocks being rabbeted at their lower bottom edges to receive the outer portions of the bottom flanges of the rails, 15 said rabbets being of less width than the said bottom flanges to space the upstanding central web of the rails from the side walls of adjacent blocks and concrete received within and filling said spaces and channels and bonding and locking the rails and blocks together.

5. The structure defined in claim 3 and sleepers embedded in the concrete and having upper surfaces lying flush with the upper edges of said rails.

PETER RUTTEN. 30
